RAZOR BLADE SHARPENER

Odgard C. Stemland, Minneapolis, Minn.

Application July 13, 1946, Serial No. 683,524

3 Claims. (Cl. 51—211)

1

This invention has relation to a razor blade sharpener.

An object of the invention is to provide a razor blade sharpener which will be of simple, practical, novel and improved construction.

And a further object is to provide a razor blade sharpener of construction as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawing forming a part of this specification,

Fig. 1 is a perspective view of a razor blade sharpener made according to the invention;

Fig. 2 is a plan view, partially broken away, of the razor blade sharpener disclosing a cover thereof in folded condition; and

Fig. 3 is a plan view, partially broken away, of said razor blade sharpener disclosing said cover in open or unfolded condition.

A flat sharpening element 10 of the razor blade sharpener is constituted as a small piece or pane of glass or equivalent which is of rectilinear configuration as disclosed.

A cover for the flat sharpening element or glass 10 consists of an exterior cover member 11 and an interior cover member 12.

The exterior cover member 11 is constituted as a flat sheet of relatively stiff material, such, for example, as card board, desirably having a roughened forward surface, and the interior cover member 12 is constituted as a flat sheet of quite flexible material, such as tissue paper, desirably having roughened forward and rearward surfaces. The exterior and interior cover members 11 and 12 are of rectilinear configuration and have approximately twice the area of the flat sharpening element or glass 10. The construction and arrangement are such that the cover members of the cover can be folded along a transverse line at the midlength of said cover so as to house or include the flat sharpening element or glass 10 between flaps of the tissue paper 12 and the card board 11.

One of the flaps, denoted 13, of the interior

2

cover member or tissue paper 12 is secured to the adjacent, rearward surface of the flat sharpening element or glass 10, and the other flap, designated 14, of said interior cover member or tissue paper is free of said flat sharpening element or glass. Also, one of the flaps, represented 15, of the exterior cover member or card board 11 is secured to the adjacent, rearward surface of the flap 13 of the interior cover member or tissue paper 12, and the other flap, indicated 16, of said exterior cover member or card board is free of the flap 14 of said interior cover member or tissue paper.

More explicitly, the rearward surface of the flat sharpening element or glass 10 is covered with a coat of paint 17, and cement, glue, or other adhesive material 18 upon substantially the whole of the forward surface of the flap 13 of the interior cover member or tissue paper 12, between the paint 17 and said interior cover member or tissue paper, firmly unites said element or glass 10 and said interior cover member or tissue paper with each other. Cement, glue, or other adhesive material 19 upon substantially the whole of the rearward surface of said flap 13 of the interior cover member or tissue paper 12, between the forward surface of the flap 15 of the exterior cover member or card board 11 and said interior cover member or tissue paper, firmly unites said exterior cover member or card board and the interior cover member or tissue paper with each other.

Clearly, the interior cover member or tissue paper 12 constitutes a bond between the glass 10 and the cover stock 11. Inasmuch as the forward surface of the flap 15 of said cover stock 11 and the rearward surface of the flap 13 of the tissue paper are rough, the cement, glue, or other adhesive material readily and easily can become caked-up between the exterior and interior cover members 11 and 12 thus to cause these to be securely united. The paint 17 constitutes a roughened surface and an additional bond between the cement, glue, or other adhesive material upon the rough, forward surface of said flap 13 of the tissue paper 12 and the glass 10 insuring that said tissue paper and glass will be securely united. It is a function of the tissue paper 12 to absorb moisture from the glass 10, and the paint 17 dresses up said glass.

The forward surface of the flat sharpening element or glass 10 constitutes a honing surface over which razor blades to be sharpened are adapted to be worked in well known manner.

What is claimed is:

1. A device of the character described comprising a flat sharpening element, and a cover for said flat sharpening element consisting of an exterior cover member constituted as a flat sheet of relatively stiff material and an interior cover member constituted as a flat sheet of flexible material, said exterior and interior cover members being substantially of twice the area of said flat sharpening element and the cover being adapted to be folded so as to include the flat sharpening element between flaps of the exterior and interior cover members, a coat of paint upon a rearward surface of said flat sharpening element, adhesive material between substantially the whole of a forward surface of a flap of said interior cover member and the rearward surface of the flat sharpening element having said coat of paint, and adhesive material between substantially the whole of a rearward surface of said mentioned flap of said interior cover member and a forward surface of a flap of said exterior cover member.

2. A device of the character described comprising a flat sharpening element constituted as a piece of glass of rectilinear configuration, and a cover for said piece of glass consisting of an exterior cover member constituted as a flat sheet of relatively stiff material such as card board having a roughened forward surface and an interior cover member constituted as a flat sheet of flexible material such as tissue paper having a roughened forward and a roughened rearward surface, said exterior and interior cover members being of rectilinear configuration and substantially of twice the area of said flat sharpening element and the cover being adapted to be folded so as to include the flat sharpening element between flaps of the exterior and interior cover members; a coat of paint upon a rearward surface of said piece of glass, adhesive material between substantially the whole of a forward surface of a flap of said interior cover member

and the rearward surface of the piece of glass having said coat of paint, and adhesive material between substantially the whole of a rearward surface of said mentioned flap of said interior cover member and a forward surface of a flap of said exterior cover member.

3. A device of the character described comprising a flat sharpening element, and a cover for said flat sharpening element consisting of an exterior cover member constituted as a flat sheet of relatively stiff material such as card board having a roughened forward surface and an interior cover member constituted as a flat sheet of flexible material such as tissue paper having a roughened forward surface and a roughened rearward surface, said exterior and interior cover members being substantially of twice the area of said flat sharpening element and the cover being adapted to be folded so as to include the flat sharpening element between flaps of the exterior and interior cover members, a coat of paint upon a rearward surface of said flat sharpening element, adhesive material between substantially the whole of a forward surface of a flap of said interior cover member and the rearward surface of the flat sharpening element having said coat of paint, and adhesive material between substantially the whole of a rearward surface of said mentioned flap of said interior cover member and a forward surface of a flap of said exterior cover member.
